E. CHIPMAN.
CRUSHING PRESS.

No. 40,325.

Patented Oct. 20, 1863.

UNITED STATES PATENT OFFICE.

EDGAR CHIPMAN, OF NEW YORK, N. Y.

IMPROVEMENT IN CRUSHING-PRESSES.

Specification forming part of Letters Patent No. 40,325, dated October 20, 1863.

To all whom it may concern:

Be it known that I, EDGAR CHIPMAN, of the city, county, and State of New York, have invented a new and Improved Press for Crushing Substances, the invention also being applicable in cases where a rolling pressure is required; and I do hereby declare that the following is a full, clear, and exact description of the same, reference being had to the accompanying drawings, making a part of this specification, in which—

Figure 1 is a side sectional view of my invention, taken the line *xx*, Fig. 2; Fig. 2, a plan or top view of the same; Fig. 3, a front or end view of the lower part of the same; Fig. 4, a detached side view of one of the adjustable ways pertaining to the same.

Similar letters of reference indicate corresponding parts in the several figures.

This invention relates to a new and improved press for crushing or pulverizing substances, and also for giving a rolling pressure—such, for instance, as is required in expressing moisture from articles or substances, and in giving impressions by means of dies, types, &c.

The object of the invention is to obtain a press for the above purposes, which will be very effective or have great power and still be capable of being operated with the greatest facility or by a trifling expenditure of power, and also be capable of being graduated so that the crushing-power may be varied or graduated as circumstances may require.

To this end the invention consists in the employment or use of a cylindrical or semi-cylindrical head or block provided with adjustable or sliding weights, and also provided with semicircular bearings having stops attached and working on adjustable ways secured to a bed, all being arranged in such a manner as to effect the desired end.

To enable those skilled in the art to fully understand and construct my invention, I will proceed to describe it.

A represents a head or block, which may be of cylindrical or semi-cylindrical form, the latter shape being preferable. This head or block may be constructed of wood or metal. If the former material be used, it may be constructed hollow or in shell form, and filled with any suitable material, *B*, to give it a re-

quisite degree of weight. If the head or block be of metal, it will probably possess sufficient weight without being filled, although, if not solid, it may be filled. The bottom of the head or block is the round or curved part, and at each side of the head or block there is an upright arm, *a*, on which a sliding or adjustable weight, *C*, is fitted. These weights may be retained by friction only on the arms *a*, or any suitable catch or fastening may be employed to hold them at any desired point on the arms.

To each side of the lower part of the head or block *A* there is attached a semicircular bearing, *D*. The ends of these bearings are extended outward a little, as shown at *bb*, Fig. 1, so as to raise the head or block as it is rolled over at either end.

E represents a horizontal bed, which has a way or guide, *F*, attached to each side of it. These ways or guides are each formed of two longitudinal parts, *cc*, placed one over the other, and having their contiguous surfaces inclined, as shown clearly in Fig. 4. Each of the parts *cc* has an oblong slot, *d*, made longitudinally in it, and through the slots a screw, *e*, passes into the bed *E*. These screws *e* hold the two parts *cc* of the ways in proper position, and also hold the ways to the bed. The bearings *D* rest on the ways *F*, the rounded part of the head or block projecting down a trifle between the ways, as shown clearly in Fig. 3. To each bearing *D*, near each end, there is attached a button, *G*, of circular form, a segment being removed or cut off from each, so as to leave a plane surface, *f*. These buttons are attached to the sides of the bearings *D* by screws *g*, which pass eccentrically through them, as shown by the dotted lines in Fig. 1.

The operation is as follows: Suppose, for instance, an article or substance is to be crushed. It is placed on the bed *E*, and the weights *C* are raised or lowered on the arms *a* to such points that the head or block *A* will be balanced. By this means the head or block may be rocked or oscillated with the greatest facility and with a trifling expenditure of power, the bearings and ways keeping the head or block in proper position on the bed. The substance or article on the bed *E* is crushed by the action of the head or block,

and the substance may be reduced to a greater or less degree of fineness by adjusting the two parts *c c* of the ways *E*—that is to say, by drawing them longitudinally outward or inward, (see Fig. 4)—by which means the head or block may be adjusted at a greater or less distance above the surface of the bed *E*. At the termination of each movement of the head or block *A* the latter is raised a trifle, in consequence of the projecting ends *b* of the bearings *D*. This raising of the head or block is important in many cases, as it enables articles to be placed readily under the head or block and removed from underneath it. The buttons *G*, when their plane surfaces *f* are in contact with the ways *F*, hold the head or block in an inclined position, as shown in red in Fig. 1.

When the device is used as a roller-press, the pressure of the head or block may be nicely graduated by adjusting the two parts *c c* of the ways *F*, as previously described.

Having thus described my invention, what

I claim as new, and desire to secure by Letters Patent, is—

1. The cylindrical or semi-cylindrical head or block *A*, provided with the sliding or adjustable weights *C*, fitted on arms *a*, in connection with a bed, *E*, all arranged substantially as and for the purpose herein set forth.

2. The bearings *D*, attached to the sides of the head or block *A*, in connection with the ways *F* on the bed *E*, for the purpose specified.

3. The ways or guides *E*, constructed of two longitudinal adjustable parts, *c c*, substantially as shown, in combination with the counterpoised head or block, for the purpose specified.

4. The buttons *G*, attached to the bearings *D*, and constructed substantially as shown, for the purpose of holding the block in an inclined position when tilted or turned on either end, as set forth.

EDGAR CHIPMAN.
